UNITED STATES PATENT OFFICE

2,493,813

WEARING APPAREL

Hyman, Simon Greenblatt, Newton Highlands,
and Julius Cohen, Mattapan, Boston, Mass.;
said Cohen assignor to said Greenblatt

Application January 17, 1947, Serial No. 722,528

1 Claim. (Cl. 2-237)

1

This invention relates to wearing apparel, such as slacks, culottes, jumpers, dresses, etc., and its principal objects are to provide an article of this type having a waist which may readily be adjusted so as comfortably to fit the waist of the wearer and to provide a construction which is of simple design and of pleasing appearance and which can be economically manufactured.

Another object is to provide an article of the afore-mentioned type which is so constructed that its length may be readily adjustable and securely held in any one of several positions of adjustment.

Further objects relate to various features of construction and will be apparent from consideration of the following description and the accompanying drawings, wherein—

Fig. 1 is a front view of a pair of slacks constructed in accordance with the present invention;

Fig. 2 is an enlarged fragmentary front view showing one of the pair of adjustable waist sections;

Fig. 3 is an enlarged section on the line 3-3 of Fig. 1;

Fig. 4 is an enlarged section on the line 4-4 of Fig. 1; and

Fig. 5 is an enlarged section illustrating the manner in which the legs are secured in a selected position of adjustment.

Referring to Figs. 1 to 3 of the accompanying drawings, which show what is now considered a preferred embodiment, the numeral 1 designates a pair of slacks which is illustrative of an article of wearing apparel having a waist 2 and a depending circumferential portion such as legs 3, and except for the parts hereinafter described, the construction and design may be in accordance with accepted conventional practices.

The waist 2 is formed with one or more adjustable parts 5, here shown as being conveniently located at each of the front lateral portions. Each of the adjustable parts 5, as shown in Figs. 2 and 3, comprises a rear section 6 and a front section 8 having opposed free end portions arranged to be drawn and held in overlapping relationship, as shown in Figs. 1 and 3.

Each of the rear sections 6 comprises a waistband element 10 consisting of two plies of fabric stitched to the front or panel portion of the slacks, and the free ends of the two plies are stitched to a strap 11 having spaced eyelets or the like openings 12 at its free end portion. A relatively short length of strapping material 14 is stitched to the front face of the waistband

and its free end carries a buckle 15 and a retaining loop 16 (Fig. 2).

Each of the front sections 8 likewise comprises a waistband element 18 consisting of two plies of fabric joining the body or panel portion of the slacks and spaced inwardly from the free end of the waistband 18 in a strap-receiving slot or opening 20 and a patch 21 overlying the opening 20 to form an open-end pocket 22 (Fig. 2) through which the strap 11 passes after being projected through the opening 20, as illustrated in Fig. 2. With this assembly each of the straps 11 may be drawn toward and threaded through the buckle 15 in the usual manner, thereby to draw the sections 6 and 8 together into overlapping relation the required degree to fit about the waist of the wearer, the free ends of the straps being passed through the retaining loop 16, as illustrated in Fig. 1. Thus, the waist of the slacks or other type of wearing apparel may be adjusted so as to assure a comfortable, well-appearing fit.

The legs 3 may also be adjusted to the desired length and, to this end, the opposite half of each leg is formed with two sections 25 and 26 (Figs. 4 and 5), the marginal portion of the section 25 being folded over and stitched to the marginal portion of the section 26 so as to form a hem 28 the lower end of which terminates in or otherwise provides a flap 30 (Fig. 4). A button or other suitable fastening element 32 is sewed to the overlapping junction of the two sections beneath the flap 30 and above the flap the hem 28 is formed with spaced button-holes 33 or fastening elements interengageable with the fastening element 32. With this construction and arrangement of parts the lower ends of the legs 3 may be folded inwardly so that each of the buttons 32 may be inserted in one of the associated button-holes 33, as shown in Fig. 5, thereby to adjust the length of the leg to suit the wearer.

An outstanding advantage of the construction and arrangement herein shown is that an article of wearing apparel, such as a dress, pair of slacks, a skirt or the like, may be so adjusted as to fit different size waists and leg lengths. Hence, such an article of wearing apparel may be made in a relatively few size ranges and any selected size range will insure a comfortable and well-appearing fit for any size within the specified range.

While we have shown and described one desirable embodiment of the invention, it should be understood that this disclosure is for the purpose of illustration and that various changes

and modifications may be made without departing from the spirit and scope of the invention as set forth in the appended claim.

We claim:

An article of wearing apparel of the class described, comprising a waist formed with two sections having free end portions constructed and arranged to be drawn into overlapping relation, a strap projecting from the free end of the first section, the outer face of said first section carrying one of a pair of complementary interengaging fastening elements spaced inwardly from its free end, the second section having a strap-receiving opening spaced from its free end and so arranged that said strap may be passed through said opening and drawn toward said first section, thereby to bring the free end portions of the two sections into overlapping relation, the free end portions of said strap carrying the other of said complementary interengaging fastening elements which is brought into position to engage the first of said fastening elements when the free ends of said sections are drawn into overlapping relation, and a patch-like member se-

10

20

cured about the outer face of said second section so as to conceal said strap-receiving opening and form an open-end pocket through which the said strap extends.
